[57] CLAIM

The ornamental design for a display terminal, substantially as shown and described.

DESCRIPTION

FIG. 1 is a front perspective view of the display terminal showing our new design;

FIG. 2 is a front elevational view thereof on a reduced scale;

FIG. 3 is a left side elevational view thereof on a reduced scale;

FIG. 4 is a right side elevational view thereof on a reduced scale;

FIG. 5 is a rear elevational view thereof on a reduced scale;

FIG. 6 is a top plan view thereof on a reduced scale;

FIG. 7 is a bottom plan view thereof on a reduced scale;

FIG. 8 is a left side elevational view thereof of a reduced scale, the display being tilted up;

FIG. 9 is a left side elevational view thereof on a reduced scale, the display being tilted down;

FIG. 10 is a front perspective view thereof with the retractable keyboard in the extended position.

The broken lines are shown for illustrative purposes only.
